UNITED STATES PATENT OFFICE.

PHILIP J. GILINSON, OF LOWELL, MASSACHUSETTS, ASSIGNOR TO HEINZE ELECTRIC COMPANY, OF LOWELL, MASSACHUSETTS, A CORPORATION OF MAINE.

PROCESS OF MAKING MAGNETO-GENERATORS.

Application filed January 13, 1922. Serial No. 529,048.

To all whom it may concern:

Be it known that I, PHILIP J. GILINSON, a citizen of the United States of America, and resident of Lowell, in the county of 5 Middlesex and State of Massachusetts, have invented new and useful Improvements in Processes of Making Magneto-Generators, of which the following is a specification.

This invention concerns electrical apparatus, such for example as magneto-generators and relates more particularly to a process useful in the production of such apparatus.

As usually constructed the field magnets 10 of magneto-generators are provided with iron pole pieces between which rotates the armature or rotor. Such pole pieces, whether of laminated or solid construction, are commonly fixed in position relatively to each 15 other and to the axis of the rotor by casting the metal of the generator casing around them. This may be done either by the die casting process or by sand casting. The die casting process is, however, initially expensive by reason of the cost of the necessary 20 dies, and in the subsequent practice of this process, such accurate machining of the exterior surface of the pole pieces is necessary to enable their insertion in the dies, as to 25 maintain a high cost of production. In the sand casting method, the roughly cast pole pieces are placed in the mould wherein the generator casing is to be formed and positioned as accurately as possible relatively to 30 one another and to the core. When the metal of the casing is poured into the mould the pole pieces are firmly embedded therein but it is found in practice that it is almost 35 impossible to maintain the pole pieces in proper relative position during the pouring 40 and cooling of the casing metal, so that when the pole pieces are machined to final shape, a wide air gap is formed between the pole pieces and rotor with consequent loss of 45 efficiency in the generator.

The object of the present invention is to provide for securing the pole pieces within the generator casing in such a manner as shall ensure accuracy of position of such 50 pole pieces, both with respect to each other and to the rotor axis, while at the same time facilitating and machining of such pole pieces and decreasing the cost of production.

To this end the invention may consist in 55 providing a unitary structure comprising

the two pole pieces together with spacer members integrally joined thereto. This structure is preferably formed as a cored casting, the heavy pole pieces being united by relatively thin connecting or bridge portions. After roughly boring out the cored opening in the member, the holes in the pole pieces necessary for securing the U-shaped magnets are drilled, and the connecting metal between the adjacent edges of the pole 60 pieces is sawed almost through on lines defining the edges of the pole pieces. The pole casting is then placed in the mould for the generator casing, the core passing through the roughly bored opening in the 65 casting and serving to center the latter. After the casing metal has been poured, the casing is removed from the mould and the cored opening therein is bored to reduce the pole faces to finished size. This boring 70 operation serves to break through the metal at the bottom of the saw kerfs, permitting the connecting bridge pieces to drop out, thus leaving the finished pole pieces accurately in alignment.

As illustrative of this method, reference may be had to the accompanying drawings, in which,—

Fig. 1 is an end elevation of the pole piece structure before machining;

Fig. 2 is a top plan view of the same;

Fig. 3 is a transverse cross section of the pole piece structure after machining and before incorporation of the same in the generator casing;

Fig. 4 is a transverse cross section illustrating the device of Fig. 3 as embedded in the casting forming the casing of the generator;

Fig. 5 is a cross section similar to Fig. 4, 95 but showing the pole pieces as separated and the U-magnets in position; and

Fig. 6 is a fragmentary, side elevation of the generator casing to smaller scale, showing the position of the pole pieces therein.

Referring to Figs. 1 and 2, there is shown a unitary structure illustrated as a casting and comprising the relatively heavy pole pieces 1, 2, connected by the relatively thin bridge pieces 3, 4, such pole and bridge pieces defining a longitudinal cored opening B. Extending along the lines of union of the bridge members with the respective pole pieces are outstanding fins such as 5, 6, respectively, the purpose of which will be 110

hereinafter described. The pole piece structure is formed of magnetic material, such for example as soft iron, and while illustrated as a unitary casing, it is contemplated that it might well be formed as a laminated structure, consisting of a series of sheet metal stampings suitably assembled. After the formation of the structure above described, the opening B is bored out roughly 10 as indicated at 7 in Fig. 3 whereby to provide the arcuate pole faces 1^a, 2^a. From the axis of the bore 7 the centers of drill holes 8, 9, are now laid out, such holes extending downwardly from the outer faces of the pole 15 pieces 1, 2, respectively. These drill holes are for the reception of the U-magnets hereinafter referred to, it being understood that one or more of such magnets may be employed and that corresponding numbers of 20 the openings 8, 9, will be formed in the respective pole pieces. After the drilling of the openings 8, 9, a plurality of longitudinal slots such as 10, 11, are formed at the 25 sides of the bridge pieces 3, 4, respectively, such slots serving to define the adjacent edges of the pole pieces. These slots may consist of saw kerfs extending inwardly toward the bore 7, and arranged symmetrically with respect to the axis of the bore. 30 These saw kerfs are of a depth such as to leave just sufficient metal connecting the pole and bridge pieces to maintain the integrity of the structure during the succeeding operations. After such machining of 35 the pole structure has been completed, it is placed in a two-part mould arranged for the casting of the generator casing. The pole structure may be supported in the mould by means of a core passing through 40 the bore 7 whereby it may be accurately retained in position. The mould is then filled with molten metal of a non-magnetic character, such for example as aluminum, whereby to form the generator casing 12, 45 the metal of the casing flowing around the fins 5, 6 of the pole structure and securely holding it in position. After the cooling of the casing, it is withdrawn from the mould with the pole structure securely embedded 50 therein. In this connection it may be noted that even though the pole structure as a whole should move slightly during the casting operation, the relative positions of the pole faces 1^a, 2^a would not be affected thereby. The bore 7 is now subjected to a boring operation whereby its diameter is somewhat increased and whereby the pole faces are finished as indicated at 1^b, 2^b, respectively (Fig. 5). In thus reboring the opening 7, sufficient metal is removed to break through the bottoms of the slots 10, 11, whereby the bridge pieces 3, 4 are separated from the pole pieces, such bridge pieces dropping out and leaving the pole 65 pieces as independent members unconnected

by magnetic material. The removal of the bridge pieces 3, 4 results in the formation of arcuate recesses 13 and 14 between the pole pieces, such recesses providing the desired clearance between the casing 12 and the rotating parts of the armature. The U-magnets may now be inserted in the openings 8, 9, and the device is ready for subsequent operations not related to the present invention. 75

In accordance with the method above described, it is evident that the pole pieces are maintained in relatively fixed position with respect to each other during the preliminary steps of the operation, including the rough 80 boring of the same and the embedding of such pole pieces in the casting of the casing. The integral connection between the pole pieces is of very considerable advantage in boring the same to form the pole faces thereof as it provides continuous metal 85 for engagement by the cutting tool, thus avoiding any tendency to form an elliptical bore, such as is frequently occasioned in attempting to bore out pole pieces which are 90 entirely separate from each other. Moreover, the integral connection of such pole pieces serves to prevent separation of the same or relative twisting or rotation of the parts during the casting of the casing, so 95 that but little machining is necessary thereafter to finish the pole pieces, with the result that the air gap may be made of minimum width and with resultant efficiency of 100 operation. 100

While it is preferred to secure the pole structure in the casing by casting it therein, it is contemplated that it might otherwise be secured in such casing without materially affecting the carrying into effect of the more essential steps of the process and it is further contemplated that roughly machined pole piece structures such as illustrated in Fig. 3 might well be manufactured 105 and sold for use in constructing generators or other electrical apparatus regardless of the particular mode of securing such pole structures in the casings with which they might thereafter be associated. While as 110 herein shown a pair of pole pieces are employed, it is also contemplated that a greater number might be used, the mode of constructing and securing the same in the generator casing being in all respects similar 115 to that above described with respect to the bi-polar structure herein disclosed. 120

Having thus described the invention, what I desire to secure by Letters Patent of the United States is:

1. That process of making electric generators which comprises forming a pair of integrally united pole pieces, simultaneously machining the pole faces of said pole pieces, and separating such pole pieces during the machining thereof. 125 130

2. That process of making magnetos which comprises casting a pair of integrally united pole pieces, machining the pole pieces, and thereafter separating said pole pieces.
- 5 3. That process useful in making electrical machines which comprises forming a pair of pole pieces integrally united by connecting elements, partially severing such pole pieces from said connecting elements
- 10 on lines defining the adjacent edges of said pole pieces, and thereafter machining said pole pieces whereby to finish the pole faces thereof and simultaneously to separate the connecting elements from such pole faces
- 15 along the lines of the previous partial severing.
4. That process of making pole pieces for electro-magnetic machines which comprises casting said pole pieces with integral connecting elements, partially separating said pole pieces and connecting elements by inwardly directed incisions, machining the pole pieces, and completing such separation by removing metal from the pole faces of
- 25 said pole pieces.
5. That process of making pole pieces for magnetos which comprises forming an integral, cored casting having the respective pole pieces united by relatively thin connecting metal, boring said casting whereby almost to sever the pole pieces from the connecting metal on lines symmetrical with the axis of the bore, and again boring such casting to form finished faces upon the pole pieces and simultaneously to complete the severing of the same from the connecting metal.
6. That process of forming independent pole pieces for magnetos which comprises forming an integral structure having pole pieces united by connecting elements, the lines of junction of said pole pieces and connecting elements being relatively weak, simultaneously machining said pole pieces, and separating such pieces and connecting elements along the relatively weak lines of junction therebetween.
- 40 7. That process of making magnetos which comprises forming a structure consisting of a plurality of pole pieces with integral connecting elements, arranging said structure within a suitable mould, pouring fusible material into such mould to form the magneto casing, and thereafter removing the connecting elements from between said pole pieces.
- 45 8. That mode of forming magneto machines which comprises forming a metallic structure of magnetic material having relatively light and heavy parts, securing said structure at its heavy portions to the magneto casing, machining the heavy parts of said structure to provide finished surfaces and to separate the light portions of said structure from the heavy portions thereof,
- and removing such light portions from the casing.
9. That mode of constructing magneto machines which comprises forming a casting consisting of relatively heavy pole pieces integrally united by lighter connecting members, weakening such connecting members along their lines of junction with the pole pieces, embedding the casting in the substance of the magneto casing, and breaking out the connecting members of said casting along the lines of weakening thereof.
10. That method of making magneto generators which comprises forming a cored casting having a pair of pole pieces connected by relatively thin elements, roughly boring the cored opening in said casting, partially severing the pole pieces from the connecting elements by longitudinal, external saw kerfs symmetrically spaced relatively to the axis of the bore, embedding such casting in the generator casing, and boring the opening in said casting to a diameter sufficient to break through the metal at the bottom of the several saw kerfs, whereby to separate the connecting elements from the pole pieces.
11. That process of making magnetos which comprises forming an integral structure having pole pieces spaced about a longitudinal bore, utilizing such bore for centering said structure in a mould, and filling said mould with molten material whereby to form a magneto casing having said structure embedded therein.
12. That method of making magneto generators which comprises casting an integral structure of magnetic material consisting of a plurality of spaced pole pieces and integral connecting members bridging the spaces between said pole pieces, said parts defining a longitudinal, cored opening boring said opening roughly to the desire diameter, partially separating said bridge members from the pole pieces by longitudinal saw kerfs extending inwardly toward the bore, said saw kerfs being symmetrical with respect to the axis of the bore and defining the adjacent edges of the pole pieces, inserting said casting in a mould, centering said casting therein by means engaging its bore, filling such mould with molten metal to form the generator casing, removing the casing from the mould, and reboring the opening in said first named casting to final diameter, thereby breaking out the bridge members between the saw kerfs.
13. A device for use in the construction of magneto generators comprising a plurality of pole pieces and bridge members integrally uniting said pole pieces, the pole pieces and bridge members defining a longitudinal, circular bore, said bridge members being structurally weak along their lines of union with the several pole pieces.

14. A structure for magneto generators having fixed therein a pole piece structure comprising a plurality of iron pole pieces integrally united by bridge members of the same material, said pole pieces and bridge members defining a circular bore of a diameter less than is required for the reception of the generator shaft and rotor, said pole

piece structure having longitudinal channels extending inwardly toward the bore along ¹⁰ lines defining the junctions of the bridge members and the respective pole pieces.

Signed by me at Lowell, Massachusetts, this third day of January, 1922.

PHILIP J. GILINSON.
